UNITED STATES PATENT OFFICE.

CHARLES C. COOPER, OF ATCHISON, KANSAS.

CHILL-CASTING MACHINE.

1,176,346.

Specification of Letters Patent. Patented Mar. 21, 1916.

Application filed April 29, 1914. Serial No. 825,498

To all whom it may concern:

Be it known that I, CHARLES C. COOPER, a citizen of the United States, residing at Atchison, in the county of Atchison and State of Kansas, have invented certain new and useful Improvements in Chill-Casting Machines, of which the following is a specification, reference being had therein to the accompanying drawing.

My invention relates to improvements in chill casting machines, the objects of which are first:—to provide a simple, substantial and durable machine of this class, by the use of which excellently formed metal castings can be made with the utmost ease and rapidity, second:—to so construct a chill casting machine that metal molds, or chills can easily and quickly be inserted in the machine and be readily removed therefrom, and to so construct chills for said machine that the same shall be thoroughly cooled in the minimum amount of time, and be transposable as to position in said machine, thus avoiding much loss of time both in cooling said chills, and through inadvertence or oversight in placing the same in said machine, third:—to provide automatic adjusting means for the chills, whereby their face surfaces are brought into absolute contact and register, thereby avoiding the molding of imperfect castings, or of molding fins on the same at the parting line of said chills, fourth:—to provide neat and efficient water circulating means, with draining means therefor, by the use of which water can be regulatably circulated through said chills in accordance with the size and number of molds formed in the faces thereof, and by the use of which said chills and their water circulating systems can be quickly and perfectly drained of said water. I attain these objects by the mechanism illustrated in the accompanying drawing, in which:—

Figure 1 is a vertical section on the line X—X, seen in Fig. 2, looking upward. Fig. 2 is a top plan. Fig. 3 is a horizontal section, looking downward, showing details of the water controlling means. Fig. 4 is a view in perspective of one of the chills which forms the one half part of a two part chill. Fig. 5 is a transverse section of the machine, cut vertically through the center of the mounting means of the oscillatable chill carrier, looking toward the left.

Referring to Figs. 1 and 4, chill 1 has

flanges 2 formed on its vertical edges, and water jacket 3 formed therein. Said chill is provided with inlet nipple 4 and outlet nipple 5 connected with said water jacket, and has molds 6 and register countersinks 6^a formed in the face thereof. Said chill has the one half part of a funnel shaped gate 7 formed therein for each one of said molds, and has the slope faced projections 6^b formed on its lower end. Said flanges 2 are slid downward between frame flanges 9 and 10, formed on the inner surfaces of frame sides 11. The lower ones of frame flanges 10 have inwardly projecting supporting lugs 12 formed on their edges, on which rests the bottom of chill 1. Frame side 11 has lever stop 11' secured thereon, said stop being adapted to stop lever 13 at the hereinafter described point of its movement. Said lever is secured on one end of shaft 14, rotatably mounted in said frame sides 11, which latter are secured together by tie rods 15 and 16 and by shaft 17, secured therein.

Chill 1' has tapered register studs 6^b projecting from its face, said studs being adapted to enter countersinks 6^a, for guiding and laterally holding said chills in register with each other. Otherwise said chills are alike in their form and construction. Chill 1' is provided with flanges 2', water jacket 3', nipples 4' and 5', molds 6', gate portions 7', and slope faced flanges 8', which are exact counterparts of the previously described parts 2, 3, 4, 5, 6, 7, and 8, thus providing chills 1 and 1', of such form that they are transposable as to position in the machine.

Chill carrier 18 is provided with two legs 19, formed therewith, the lower ends of which are oscillatably mounted on shaft 17. Said chill carrier has upper and lower flanges 10' formed on the inner surface thereof, against which flanges 2' are pressed for holding chill 1' in said chill carrier. The lower ones of flanges 10' have inwardly projecting supporting lugs 12' formed thereon at their lower ends, upon which chill 1' is slidably supported. Said carrier has lateral tie pieces 19' formed therewith, through which threaded apertures 19'' are formed for the reception of tension screws 20, through which said screws are screwed for adjusting the tension of springs 21, mounted on spring guides 22, slidably mounted in countersinks 20', formed in the inner end

- portions of screws 20. Said spring guides have heads 22' formed on their inner ends, said heads being pressed against the back surface of chill 1', for yieldably holding said 5 chill in the position shown. Said chill carrier is provided with wrist shaft 23, secured therethrough. Each end of said wrist shaft is rod and crank connected with shaft 14, by connecting rods 24 and cranks 25.
- 10 Referring to Fig. 3, inlet pipes 26 and 26' are connected with outlet pipe 27, by pipe 28 and three-way cock 29, the latter being controlled by handle 29', seen in Figs. 1 and 2, said cock being also connected with pipe 26^a 15 and adapted to open and close the same for controlling passage of water through said pipe, which is connected with a source of water supply, not shown.
- 15 Inlet pipe 26' is connected with nipple 20 4 by pipe and connections 26'' for conducting water therefrom into water jacket 3. Nipple 5 is connected with pipe 27, by pipe 25 connections 27''.
- 20 Inlet chamber 17' is connected with nipple 4', by jointed pipe connections 17^a (see Figs. 2 and 3,) while chamber 17'' is similarly connected with nipple 5', by jointed pipe connections 17^b. Said chambers are formed in the end portions of shaft 17. Inclined trough 31 has its lower end secured on tie rod 16, the upper end of said trough being supported by trough legs 31', the lower ends of which are securely mounted on base 11'' of frame sides 11, (see Fig. 1,) 25 said trough being adapted to support and guide castings 32, which gravitate thereon, from chills 1 and 1'. Said castings gravitate along said trough, and therefrom onto any suitable receptacle not shown. Before 30 chill 1' is placed in the position shown, heads 22' are elastically held in a position, slightly toward the right from the position seen, by springs 21, extended to their elastic limit. While said chill is being inserted and 35 lowered to position in carrier 18, projections 8' pass in front of the lower ones of heads 22', moving said heads to the position shown, thereby compressing their springs 21.
- 40 In operation, with the parts in the position seen in Fig. 1, water under pressure in pipe 26^a, (see also Fig. 3,) circulates continuously through chills 1 and 1', while the machine is in use, as hereinafter described. Said water flows through pipe 26^a, cock 29 45 and pipe 26, from whence a portion of said water flows through pipe connections 26'' and nipple 4, into water jacket 3, upward through said jacket, and thence through nipple 5, pipe connections 27'' and outlet pipe 27, into any suitable receptacle, (not shown,) such as a sewer, tank or the like. While water is thus circulating through water jacket 3, of chill 1, the remaining portion 50 of said water which has passed through cock 29 and pipe 26, passes through pipe 26', into inlet chamber 17', and thence through the jointed pipe connections 17^a and nipple 4' into water jacket 3' of chill 1'. Said water passes upward through said jacket and thence through nipple 5' and jointed pipe 70 connections 17^b, into outlet chamber 17''. Said water flows from said chamber, through pipes 27' and 27, into the previously described receptacle.
- 55 In making castings, the operator not shown, rotates lever 13 until the same is stopped on lever stop 11', which by the previously described shaft, rod and crank connections draw chill carrier 18 toward the right until chill 1', (guided by register studs 6^b,) is in register and in contact with chill 1. Said operator then adjusts the tension of springs 21, by screws 20 to a sufficient pressure to overcome such static pressure as the hereinafter mentioned molten metal exerts in the previously described molds, and maintain absolute contact of the face of chill 1' against the face of chill 1. The parts are detachably held in this position, by the gravity of handle 13, stopped on stop 11, and 60 also by reason of the fact, that cranks 25 and connecting rods 24 act as the limbs of toggles, in holding chill carrier 18. Said operator pours molten metal, not shown, into the described funnel shaped gates, thereby 65 filling said molds and partially filling said gates, which the previously described circulation of water cools very quickly. When the thus formed castings 32, are sufficiently cooled, the operator moves lever 13 from 70 stop 11', back to the position shown; upon which said castings gravitate from the described molds into trough 31, from whence they gravitate onto any suitable receptacle, 75 not shown. Said operator repeats the previously described actions as long as desired, thereby rapidly molding a large number of clean, well formed castings, in a comparatively short space of time.
- 80 Chills 1 and 1', together with their pipe connections are drained by rotating cock handle 29', and thereby closing pipe 26^a, and at the same time opening communication through said cock, between chamber 17' and pipe 28, upon which both of said chills 85 will be drained through their previously described pipe and chamber connections and pipe 27 into the before mentioned receptacle.
- 85 Having fully described my invention, what I claim as new and desire to secure by Letters Patent is:—
- 90 1. In a chill casting machine, the combination of a two part chill adapted to have castings molded therebetween, of a frame for said machine; chill holding means in said frame wherein one of said parts of said chill is detachably held; a chill carrier; carrier legs formed with said carrier the lower ends of said legs being oscillatably mounted in the lower end portion of said frame; car-

- rier chill holding means in said carrier whereon the other part of said chill is slidably supported; yieldable holding means in said carrier whereby said other part is yieldably held against backward movement; and oscillating means whereby said carrier is oscillated for carrying the therein carried other chill part against the first mentioned part of said chill.
- 10 2. In a chill casting machine, a frame for said machine; a chill section mounted in said frame; a chill carrier oscillatably mounted on said frame; another chill section, said other section being slidably mounted in said carrier; stopping means in said carrier for limiting forward movement of said other section; yieldable holding means in said carrier whereby said other section is yieldably held against said stopping means; adjusting means whereby said yieldable holding means are adjusted and oscillating means whereby said carrier is oscillated for carrying said other section against the first mentioned section and elastically pressing the same thereagainst.
- 15 3. In a chill casting machine, an oscillatably mounted chill carrier having transverse tie pieces formed therewith at the back thereof; stop flanges formed on each of the two front edges of said carrier; supporting lugs formed on the lower ends respectively of said flanges; adjusting screws screwed through said tie pieces; spring guides portions of which are slidably guided in the inner end portions of said screws; heads on said guides; springs mounted on the remaining portions of said guides between said heads and screws; a chill section forming a part of a chill or mold the vertical edges of said section being placed between said stop flanges and said guide heads the bottom of said section resting slidably on said lugs; and slope faced projections on the lower edge of said section.
- 20 4. In a chill casting machine; a frame; chill holding means adapted to hold a chill in said frame; a chill in said holding means; a chill carrier oscillatably mounted on said frame; carrier chill holding means formed with said carrier; a counterpart chill slidably mounted on said carrier chill holding means; stopping means formed with said carrier for stopping forward movement of the thereby carried chill; yieldable holding means for holding said counterpart chill against said stopping means when said chill is in operative position, both of said chills
- 25 being of the same size and shape and being transposable as to position in said machine; and slope faced bottom flanges formed on the bottoms of both of said chills said bottom flanges being, adapted to backwardly move the lower ones of said yieldable holding means while their respective chill is being placed in said position.
- 30 5. In a chill casting machine, a frame; chill holding means in said frame; a chill section detachably mounted in said frame; a water jacket formed in said chill section; water inlet means; water controlling means in said inlet means; jointed pipe connecting means whereby the lower portion of said water jacket is connected with said water inlet means; water outlet means; jointed outlet pipe connections whereby the upper portion of said water jacket is connected with said water outlet means; and closable pipe connections whereby said water controlling means and said water outlet means are connected.
- 35 6. In a chill casting machine, a frame; a shaft secured transversely through the lower portion of said frame; an inlet chamber formed in one end of said shaft; an outlet chamber formed in the other end of said shaft; water inlet means connected with said inlet chamber; water controlling means in said inlet means; water outlet means connected with said outlet chamber; closable pipe connecting means whereby said controlling means and said outlet means are closably connected; a chill carrier; a chill section detachably mounted in said carrier; mounting means whereby said carrier is oscillatably mounted on said shaft; a water jacket formed in said chill section; jointed pipe connections one end of which is oscillatably connected with said inlet chamber while the other end of said connections is connected with the lower portion of said water jacket; jointed outlet pipe connections one end of which is oscillatably connected with said outlet chamber while the other end is connected with the upper portion of said water jacket; and oscillating means whereby said chill carrier is oscillated.
- 40 In testimony whereof I affix my signature in the presence of two witnesses.
